HEAD FOR A TOY STICK HORSE

Mildred S. Anderson, Pueblo, Colo.

Application October 12, 1953, Serial No. 27,130

Term of patent 7 years

(Cl. D34—15)

To all whom it may concern:

Be it known that I, Mildred S. Anderson, a citizen of the United States, residing at Pueblo, in the county of Pueblo, State of Colorado, have invented a new, original, and ornamental Design for a Head for a Toy Stick Horse, of which the following is a specification, reference being had to the accompanying drawing, forming part thereof, and wherein:

The dominant features of my design reside in the portion shown in full lines.

I claim:

The ornamental design for a head for a toy stick horse, as shown and described.
